CLAIM

The ornamental design for an electronic cigarette, as shown and described.

DESCRIPTION

FIG. 1 is an exploded perspective view of an electronic cigarette, showing my new design;

FIG. 2 is a front, top perspective view of the electronic cigarette, shown in a fully assembled configuration;

FIG. 3 is a front, top perspective view of a first element of the electronic cigarette;

FIG. 4 is a rear, top perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a front, top perspective view of a second element of the electronic cigarette;

FIG. 12 is a rear, bottom perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof; and,

FIG. 18 is a bottom plan view thereof.

The broken lines in the figures illustrate portions of the electronic cigarette that form no part of the claimed design.

1 Claim, 18 Drawing Sheets
